UNITED STATES PATENT OFFICE.

EDGAR A. CUSTER, OF PHILADELPHIA, PENNSYLVANIA, ASSIGNOR TO CUSTER SANDLESS CASTING COMPANY, OF PHILADELPHIA, PENNSYLVANIA, A CORPORATION OF DELAWARE.

SASH-WEIGHT.

973,176.

Specification of Letters Patent. Patented Oct. 18, 1910.

Application filed December 17, 1909. Serial No. 533,617.

To all whom it may concern:

Be it known that I, EDGAR A. CUSTER, a citizen of the United States, residing in the city of Philadelphia, in the State of Pennsylvania, have invented certain new and useful Improvements in Sash-Weights, of which the following is a specification, reference being had to the accompanying drawing, forming a part hereof.

10 Sashweights intended for use with heavy window sashes are now sometimes made up and supplied in the form of interlocking sections so that as many sections may be used as are necessary to properly counterbalance the particular window sash without requiring the provision of a large number of sashweights of different weights and the selection of one suited to the particular window sash. Objection is sometimes made to 15 the use of such sectional sashweights for the reason that they may become disengaged, especially when the sashweight is permitted to strike at its lower end, and because the form of the interlock between sections is 20 such as to permit excessive movement between the sections, so that there is a possibility of their jamming in the sashweight well and is also such as to leave considerable open space between successive sections, 25 thereby requiring the total length of the sashweight to be considerably greater than that of a single piece sashweight.

The purpose of the present invention, therefore, is to improve the interlock or form 30 of connection between the sections of a sectional sashweight so that, while the connection of sections shall be easily effected and there shall be ample strength in the connection, there shall be closeness of fit of 35 parts, practically no loss of weight in the connection, no liability to accidental disconnection, comparative rigidity, and an inherent tendency to hang straight.

The invention will be more fully explained 40 hereinafter with reference to the accompanying drawing in which several embodiments thereof are illustrated, and in which—

Figure 1 is a view showing a portion of a window sash, a sashweight well and a sashweight composed of two sections. Fig. 2 is a view in side elevation, on a somewhat larger scale, of the sashweight shown in Fig. 1. Fig. 3 is a view of the same as seen from the right hand in Fig. 2. Fig. 4 is a view of the same as seen from the left hand

in Fig. 2. Figs. 5 and 6 are views illustrating modifications in the form of the interlock.

Each sashweight section *a* may have any desired dimensions and may have any suitable cross section, but is preferably rectangular in cross section, as indicated. Sections intended for the tops or bottoms of weights might be specially formed except as to the ends which interlock with adjacent sections, but for convenience in manufacture and in manipulation all sections have the same form. Each section *a* has at one end an interlocking knuckle formed of a straight shank *b*, parallel with the longitudinal axis and extending across the full width of the weight, and an under cut, slanting hook *c*, also extending across the full width of the weight, the end *d* of the body *a*, the under side *e* of the hook *c*, and the top *f* of the hook *c*, all being formed on the same slant or in parallel planes and with parallel surfaces. The top or end *d* of the body of the weight, the top or end *f* of the hook *c* and the under side *e* of the hook *c* are formed with corresponding keys and keyways, as *d'*, *e'* and *f'*. Such keys or keyways are designed to prevent lateral relative displacement of successive sections, as explained hereinafter, and may therefore have any suitable form by which such result may be accomplished, being angular, as shown in Figs. 3 and 4, or curved in the arc of a circle, as shown in Fig. 5, or formed as a rounded ridge, as shown in Fig. 6. It is also immaterial, as will be obvious, whether the keys or elevations be formed on the surfaces *d* and *f* and the keyway or depression be formed in the underside of the hook *c*, as shown at the upper ends of the sections, or be reversed, as shown at the lower ends. The other end of each section is likewise formed with an interlocking knuckle consisting of a shank *g* and a hook *h*, and is formed with keys and keyways or ridges and depressions similar to those at the other end but reversed, so that the interlocking knuckle at one end of a section is the exact complement of the interlocking knuckle at the other end of the section. It will now be seen that since the sections are formed alike, each section may be connected to the next by hooking its knuckle into the complementary knuckle of the next section. Since each hook is under cut on a straight,

oblique line and the upper section is suspended from above, the weight of each lower section will draw it into and maintain it in line with the section above. Furthermore, 5 the complementary keys and keyways prevent lateral relative displacement of one section with respect to another. Again, since one straight, sliding knuckle is the exact and full complement of the other 10 knuckle of the interlocking pair of knuckles, there is no space between sections to cause loss of weight or to permit one section to swing out of line with respect to the next section.

15 The forms of interlocking knuckles shown in Figs. 2, 3, 4 and 6, not only prevent lateral relative displacement of sections, but they prevent swinging of one section with respect to another, even when the weight is 20 not suspended in a well. The form of knuckle shown in Fig. 5, however, while preventing lateral relative displacement, does permit swinging of one section with respect to another, since the hook is curved 25 laterally on the arc of a circle, but such swinging cannot take place when the weight is suspended in the usual well. Each weight is provided in its hook *c* with a hole *i* to receive the end of the sash cord *k* which may 30 be knotted underneath the hook, as at *k'*. The hole *i* is formed in the line of the axis of the section and the section will, therefore, hang perfectly straight from the cord. As each section has with the next section a 35 bearing in a line which is symmetrical with respect to the vertical axis, each section hangs in a straight line with the one above it.

It will be obvious that if the sectional sashweight, when suspended from above and 40 descending, should be allowed to strike on its lower end, the straight, sliding hooks would permit disengagement of the sections if the sections were not held from relative displacement by the walls of the 45 well. It may be thought desirable, in cases where the walls of wells cannot be depended upon to prevent relative displacement of the sections, to guard against such displacement. Accordingly, the angle of the hook *b*, *c*, may 50 be recessed or chamfered off, as at *l*, and the other end of the same face or side of the weight may be provided with a low, complementary rib *m*. The height of the rib *m* does not exceed the extent of play between 55 the sections, so that it does not prevent the engagement of one section with another, but

it will be obvious that if the lower end of a sectional weight is about to strike while the weight is descending, the play between successive sections will be taken up and the rib 60 *m*, although low, will enter the corresponding depression *l*, that is, will engage the top of the hook *c* of the next section and will prevent the sliding of one section relatively to the next section. 65

It will now be understood that by the formation of the straight, sliding interlocking knuckles as described, especially with a key or rib or ridge transverse to the face of the knuckle, the desirable features of a sectional sashweight can be combined and facility in connection, maintenance of alignment and nonliability to accidental displacement be secured at a minimum cost of manufacture. It will also be obvious that various changes may be made to suit the convenience of the manufacturer or the desires of the user and that the invention is not restricted to the precise forms shown and described herein. 70 75 80

I claim as my invention:

1. A sectional sashweight having at each end a straight, slanting knuckle with parallel surfaces, the knuckle at one end being the complement of the knuckle at the other end, 85 such sectional sashweight being adapted to be engaged with and disengaged from the next by bodily oblique movement with its axis parallel with that of the next.

2. A sectional sash weight having at each 90 end a straight, slanting interlocking knuckle with parallel surfaces, the knuckle at one end having a transverse key and the knuckle at the other end having a complementary keyway, such sectional sashweight being 95 adapted to be engaged with and disengaged from the next by bodily oblique movement with its axis parallel with that of the next.

3. Sectional sashweights having straight, slanting interlocking knuckles with a low 100 rib across the end of one section to engage the adjacent end of the next section to prevent disengagement of the knuckles when the lower section is held from movement downward. 105

This specification signed and witnessed this 15th day of December A. D. 1909.

EDGAR A. CUSTER.
